UNITED STATES PATENT OFFICE.

SYLVANUS H. COBB, OF BOSTON, MASSACHUSETTS.

RULING-MACHINE.

1,206,989.

Specification of Letters Patent.

Patented Dec. 5, 1916.

Application filed October 4, 1913. Serial No. 793,497.

To all whom it may concern:

Be it known that I, SYLVANUS H. COBB, a citizen of the United States, residing at Boston, in the county of Suffolk and State of Massachusetts, have invented a new and useful Ruling-Machine, of which the following is a specification.

The present invention concerns ruling machines, and more especially that type in which the pens or other ruling devices are electromechanically actuated. Its chief objects are to apply to the ruling devices, with the interposition of few moving parts, forces acting to vary the relation of the ruling devices to the work, and to so control such application that the time of ruling contact is as brief or as long as desired. Moreover, this control may be exercised over the ruling devices individually or in groups, which may readily be altered to meet the requirements of any particular form to be ruled. Both the actuation of the ruling devices and their control is effected noiselessly.

The accompanying drawings illustrate one embodiment of the invention, Figure 1 being a side elevation, parts being broken away; Fig. 2 a transverse section on the line 2—2 of Fig. 1, with parts omitted; Fig. 3 an enlarged broken section through the contact wheel on the line 3—3 of Fig. 1; Fig. 4 an enlarged side elevation of the contact brushes and their support; Fig. 5 a transverse section on the line 5—5 of Fig. 4; Fig. 6 an enlarged broken perspective view of a pen-actuating unit and two of the sockets therefor, the parts being separated; and Fig. 7 a diagram of the electrical circuit for the machine.

Supported on a frame 10 are the usual feed-rolls 11, 11, which, with a belt 12 operating over the lower roll and a roll (not shown) at the opposite extremity of the frame, feed the sheets to be ruled over a table 13 through the machine. Power may be applied to one of the feed-roll shafts from any convenient source, these shafts being connected to rotate in opposite directions by gears 11a.

Adjacent to the table 13 is a beam 14 pivotally mounted upon adjustable standards 15 and carrying pens or other ruling devices 16. The pen-beam and its supports may be of the well-known flexible form, and need not be here described. The pens resemble those customarily employed, except that they are preferably each provided with

means, as an opening or eye furnished by hook 17, by which they may be connected to the actuating means to be later described. A screw 18 carried by the beam and contacting with a bracket 19 from one of the standards 15 allows the angular adjustment of the beam with relation to the work, the screw being drawn normally against the bracket by the spring 20 extending between the beam and frame.

The standards 15 are shown as having upward extensions 21 furnished at their inner sides with brackets 22, of which three are illustrated upon each standard. Mov- 70 able upon the upper face of each bracket is a block 23 of insulating material, the pairs of blocks situated at the same level being joined by shelves or supports 24 which are in the form of angle-beams. At the side of 75 the machine opposite that at which the operator stands the blocks 23 are guided by spindles 25 projecting horizontally from them through openings in the standard. At the other side, or toward the operator, there 80 are sockets in the outer faces of the blocks to receive the enlarged ends of screws 26 threaded through the standard and preferably retained in place by lock-nuts 27. This manner of mounting the shelves enables 85 them to be adjusted laterally of the machine, or longitudinally of the series of pens.

Fixed to the top of each shelf or support is a strip 28, preferably molded from fiber or other insulating material, of comb-like form with separated projections 29 having overhanging portions 30 furnishing sockets located above the pen-beam to receive electromagnetic actuating devices for the pens. These devices are in the form of inter- 95 changeable units, any one of which may be applied to any socket for the operation of any pen. Each device, as illustrated, comprises a conducting base or plate 31 of such dimensions as to fit within the sockets, and having secured to it an electromagnet of the return-pole type comprising a yoke 32 consisting of a horizontal member lying between the portions 30 of the socket-strip and carrying a magnet spool and core 33, and a vertical member upon the upper extremity of which is pivoted the armature-lever 34. At the inner side of the magnet, or opposite the vertical member of the yoke, an insulated block 35 is fixed to the base, having in conductive connection a soldering lug 36 and a rounded terminal 37. One end

of the magnet winding is joined to the lug 36, while the other extremity of the winding is soldered to a similar lug 38 fixed to the yoke or base. When an actuating device 5 is inserted in a socket the terminal 37 is engaged by a spring terminal 39 attached to the socket-strip 28 and having a soldering lug 40 for connection with the conductors of a cable.

- 10 The outer end of each armature lever 34 is bifurcated at 41 and in the separated arms are depressions 42 to receive a rounded supporting and adjusting nut 43. Through this nut passes a screw or spindle 44, which may 15 be locked by a nut 45 and retained against upward movement by a nut 46 below the lever. This furnishes an adjusting device which is freely separable from the armature through the opening at 41. At the lower 20 extremity of the screw is an eye 47 to receive a flexible tension member 48, preferably furnished by a wire which is secured to the eye 47 and is twisted at its lower end into an eye at 49 for engagement with the hook 25 17 of a pen. It will be evident that when one of the electromagnetic units is in place in a socket and is energized, the outer end of the lever 34 is raised by the resulting attraction of the armature, and the pen to 30 which the wire is attached is lifted, said pen yielding at its shank to permit this. When the magnet is deenergized the spring of the shank returns the pen into contact with the work. The normal tension of the 35 wire may be adjusted by means of the nuts 43, 45 and 46, so that when no current flows through the magnet the pen will rest on the belt or sheets to be ruled, yet the lifting effect may be exerted without lost motion. 40 The sockets for the magnets are so placed that pens in close proximity to one another may be independently operated, the arrangement in plural tiers giving an opportunity for the placing of the relatively wide actuating units above the narrow pens. It 45 is, of course, desirable that the pull on the pens shall be substantially vertical, or directly away from the work. This may be obtained by an adjustment of the supporting shelves 24 by means of their screws 26.

It may sometimes happen that a movement of all the pens of the series must be simultaneously effected, and to this end means is provided for rocking the entire 50 beam on its standard. Projecting rearwardly from one end of the beam is an arm 55 which may have an adjustable connection 51 to the beam found in ruling devices of the cam-operated type. This arm carries an armature 52 of an electromagnet 53 supported on the frame, which magnet exercises such an attractive force that upon its energization the beam will be rocked on its pivots against the tension of the spring 58 and all the pens raised from the work.

To determine the application of current to the magnets, which current may flow from a generator 54 belted to one of the shafts of the machine or from any other suitable source of electrical energy, controlling means is interposed between said source and the magnets, furnishing a common current-distributing means for the latter; and since even in the most complicated forms the movement of many of the pens is the same, the controlling means is arranged to act on the electromagnets in groups. From the frame at the rear of the ruling and actuating devices rise standards 55 in which is journalized a shaft 55^a. Rotation is imparted to this shaft through a gear 56 fixed thereto and meshing with a large idle gear 57 cooperating in turn with the lower feed-roll gear 11^a. The gear 57 is mounted on a stud 58 adjustable along a segmental slot 85 in an arm 59 depending from the frame, said slot having the center of the lower gear 11^a as an axis. The speed of rotation of the shaft 55^a with respect to the feed elements may be changed by substituting gears 56 of different diameters and correspondingly shifting the gear 57. Carried by the shaft 55^a are the rotatable elements of a number of pen-controlling contact devices, said number depending upon the distinct group-movements the pens are to receive. Each rotatable element consists of a wheel 60 fixed to the shaft 55^a and having at one side of its periphery a circumferential recess 61 and in the same side toward the center of the wheel an adjacent concentric circumferential recess 62. In the latter recess is secured by screws 63 a ring 64 of insulating material, the periphery of said ring lying farther from the shaft than the edge of the wheel. In the recess 61, which with the ring 64 forms a channel, metal contact blocks or segments 65 are situated projecting just outside the ring, which blocks may conveniently be in pairs side by side, clamped in place by the ring and movable with respect to one another so the extent of contact surface can be varied. A single block 66 of double thickness of the desired extent may instead be employed.

With each wheel 60 cooperates a normally stationary element of the contact device. This is preferably supported on the shaft 55^a by means of an arm 67 extending from a hub 68 embracing the shaft. At the outer extremity of the arm is a flange 69 overhanging the periphery of the wheel. At the rearward edge of the flange is secured a holder 70 between the separated sides of which is pivoted a nut 71. A screw 72, mounted to turn in a bracket 73 carried by a bridge-piece 74 between standards 75, 75 rising from the frame of the machine, engages the nut and holds the arm 67 against rotation, the angular position of the arm 130

being adjustable by turning the screw. Near the forward edge of the flange is fixed an insulating block 76 from which projects a brush-support 77. Two of these 5 brushes or contact-projections are shown, one, 78, being merely pivoted on the support in a holder 79 and pressed by a spring 80 against the insulating ring 63 or against the contact blocks 65 and 66, depending 10 upon the position of the wheel 60. The holder 79 of the other brush 81 is pivoted under the influence of a second spring 80 upon a slide 82, adjustable circumferentially of the wheel in ways in the support 15 77 by a screw 83 rotatable in an arm 84 of the support and threaded through the slide. At any convenient point on the support may be secured a soldering lug 85 for connecting the two brushes in parallel 20 to the circuit. Considering the contact wheels as rotatable in the direction of the arrow in Fig. 1, it appears that the brush 78 will first be engaged by the contact blocks and lifted from the insulating ring 25 to close the circuit at this point, and that thereafter said block leaves the brush 81 to again open the circuit. In a preliminary way this connection may be controlled by positioning the blocks in their channel before the machine is started, but thereafter 30 at any time in the operation if the timing is not correct, the brushes may readily be moved together by the screw 72 until the making of the contact is as desired, and 35 then the brush 81 further adjusted by the screw 83 to give the precise time of breaking the contact.

An electromechanically controlled gate 40 for governing the delivery of the sheets to be ruled to the pens is also preferably provided. This gate comprises a shaft 86 journaled in the standards 55 and having along it holders 87 in which gate-fingers 88 are fastened by set-screws 89. From 45 an arm 90 on the shaft 86 a spring 91 extends to the frame to draw the fingers against the feed-belt. To raise the gate for the purpose of releasing a sheet, an arm 90^a carries an armature 91^a of an electromagnet 92, which is supported upon the frame and supplied with current at the proper time through a current-controlling device such as has just been described.

The circuit for connecting the pen-beam 55 and gate-actuating devices and the controlling devices is illustrated in Fig. 7. Mounted on the frame convenient to the operator is a switchboard 93, which may be of the telegraph pattern, having vertical bars 60 94 of which there should be one for every actuating device socket and one each for the beam and gate-magnets, and intersecting horizontal bars 95, one for each controlling device, these bars being separated 65 and insulated from one another. Openings

96 in both sets of bars allow any bar 94 to be connected to any bar 95 by means of plugs 97. One pole of the generator 54, the other pole of which may be grounded upon the frame, is joined by conductor 98 70 and its multiple branches to the shelves 24, and so to those terminals of all the magnet-windings which are united to the lugs 38. The other terminals of the magnets, through the lugs 36, are separately 75 joined by conductors 99 contained in cables 100 supported on the standard-extensions 21 to the bars 94. The bars 95 are respectively connected to the brush-pairs of the controlling devices through the lugs 85 and 80 conductors 101 formed in a cable 102 carried by the standards 75, the contact blocks 65 and 66 being in conductive connection with ground through the wheel 60 and so with the grounded pole of the generator. 85

In using the apparatus the pens are adjusted in their beam in the customary manner, one for each line to be ruled. Over each pen which is to have an independent lift an actuating unit is inserted in the 90 socket which is vertically alined with the pen, the act of insertion effecting connection of the magnet-coils of the units with their switch-bars 94. The loops of the unit wires 48 are caught into the pen-hooks 17, 95 and the nuts on the spindles 44 are adjusted to give the proper tension. A contact-wheel 60 is selected for each group of movements in which a plurality of pens are to share, and the contact-blocks therein adjusted to 100 give approximately the desired lift and release of the pens in correct timing. The actuating units may then be grouped in circuit with the brushes of the respective wheels by placing plugs 97 in the openings 105 96 of the switchboard to join the switch-bars 94 of the actuating units to the switch-bars 95 of the proper controlling units. The gate-magnet 92 is connected through the switchboard with its contact wheel or may 110 be directly placed in circuit therewith; if there is to be a simultaneous lift of all the pens the beam-magnet 53 is also brought into play. The machine is then started, and if the lifting and striking points of the pens 115 are not perfect, these may be separately adjusted for the pen-magnets and beam-magnet by turning the screws 72 and 83 until the errors are corrected, it being unnecessary to stop the apparatus to do this. The 120 timing of the gate may be similarly controlled.

In addition to the ease with which my improved machine may be set and operated to correctly rule intricate forms, it will be observed that no lift of the pens nor break in the ruled lines is too brief for it to accomplish with precision. For this purpose the contact-ends of the brushes 78 and 81 may be brought into such close proximity 130

that they furnish a continuous, narrow contact-surface, and the contact-block of the wheel may be made of as limited extent as desired. Then, since the electromagnetic action is, in effect, instantaneous for a suitable quick-acting magnet, and as the inertia of the moving parts is slight, the return of the pen to the sheet may occur immediately upon its removal therefrom.

10 I claim as my invention:

1. The combination with a plurality of ruling devices, of plural electromechanisms each adapted to actuate a ruling device, a source of current, and means common to different electromechanisms for controlling the application of current thereto.

2. A ruling machine comprising a series of ruling devices, electromechanical means for imparting independent movement to each of a plurality of the ruling devices of the series, and independent electromechanical means for simultaneously imparting movement to all the ruling devices of the series.

25 3. The combination with a plurality of ruling devices, of plural electromechanisms each adapted to actuate a ruling device, a source of current, and common controlling means for different electromechanisms, said controlling means having elements for determining the application of current to the electromechanisms in groups.

4. A ruling machine comprising a series of ruling devices, an electromechanism individual to each of a plurality of ruling devices for moving the same, means for controlling the energization of said electromechanisms in groups, and a separate electromechanism acting on a plurality of the groups.

45 5. A ruling machine comprising a series of ruling devices, an electromechanism individual to each of a plurality of ruling devices for moving the same, means for controlling the energization of said electromechanisms in groups, and means for connecting any of the electromechanisms to any of the group-controlling means.

50 6. A ruling machine comprising a series of ruling devices, an electromechanism individual to each of a plurality of ruling devices for moving the same, means for controlling the energization of said electromechanisms in groups, and a switchboard 55 to which both the electromechanisms and group-controlling means are connected.

7. The combination with a plurality of ruling devices, of an electromechanism for actuating each ruling device, each actuating 60 mechanism being usable interchangeably with various ruling devices.

8. In a ruling machine, a beam, a flexible pen held fixedly in the beam, an electromagnet and its armature, and a connecting member attached to the armature and pen

and acting to flex the pen in the beam upon movement of the armature.

9. The combination with a ruling device, of a support in which a portion of the device is held fixedly, an electromagnet and its armature situated above the ruling device, and a connecting member loosely supported upon the armature and engaging a portion of the ruling device projecting from the support.

75 10. The combination with a ruling device, of an electromagnet and its armature, an adjusting device carried by the armature and being freely separable therefrom, and a connection between the adjusting and ruling devices.

11. In a ruling machine, a pen, a belt traveling beneath the pen and with which it contacts, an electromechanism mounted above the pen, and a flexible connecting member between the electromechanism and pen for lifting said pen from the belt.

85 12. The combination with a ruling device, of an electromagnet and its armature situated above the ruling device, a nut resting on the armature, and a connecting member threaded through the nut and engaging the ruling device.

90 13. In a ruling machine, a pen, a belt traveling beneath the pen and with which it contacts, an electromechanism mounted above the pen, and a flexible connecting member between the electromechanism and pen for lifting said pen from the belt, said connecting member being separable from the electromechanism by merely lifting it from engagement therewith.

95 14. The combination with a ruling device, of an actuating lever therefor, a nut resting on the lever, and a connecting member threaded through the nut and engaging the ruling device.

105 15. The combination with a ruling device, of an actuating lever therefor, a nut resting on the lever, a member threaded through the nut, and a flexible member connecting the threaded member and ruling device.

110 16. The combination with a ruling device, of a lifting lever therefor, a screw extending through the lever, and a connection between the extremity of the screw and ruling device.

115 17. In a ruling machine, a beam, a clamp carried thereby, a series of pens fixed between the clamp and the beam, an electromechanism, and means depending from the electromechanism for engaging one of the pens.

120 18. In a ruling machine, a beam, a clamp carried thereby, a series of pens fixed between the clamp and the beam, an electromechanism, and a flexible connection between the electromechanism and one of the pens.

19. In a ruling machine, the combination with a beam, of a series of pens fixed therein, a plurality of electromechanisms, connections between certain of the electromechanisms and certain of the pens, and means for variably controlling the electromechanisms. 5
20. The combination with ruling devices, of a support provided with sockets, and an electromechanical actuating device for the ruling devices adapted to coöperate with any one of a plurality of sockets. 10
21. The combination with a ruling device, of a support provided with a socket, and an electromechanical actuating device for the ruling device coöoperating with the socket, said actuating device and socket having coöperating contact terminals. 15
22. The combination with a ruling device, of a support provided with a socket, and an electromechanical actuating device for the ruling device coöperating with the socket, said actuating device and socket having coöperating contact terminals adapted to engage one another to retain the actuating device in its socket. 20
23. In a ruling machine, ruling devices, a plate, a strip of insulating material secured to the plate and having recesses, and electromechanical actuating devices for the ruling devices adapted to enter the recesses. 30
24. In a ruling machine, ruling devices, a conducting plate, insulating material secured to the plate and having recesses, a terminal carried by the insulating material, a conductive base adapted to enter the recesses, an insulated terminal on the base adapted to engage that on the insulating material, an electromagnet mounted on the base and having its winding connected to said base and to the insulated terminal thereon, and a source of electrical energy joined to the plate and its insulated terminal. 35
25. The combination with a series of ruling devices, of a support, actuating means for the ruling devices mounted on the support, and means for varying the position of the support longitudinally of the series of ruling devices. 45
26. The combination with a series of ruling devices, of supports situated in different vertical positions, actuating means for the ruling devices mounted on each support, and means for varying the position of each support longitudinally of the series of ruling devices. 55
27. The combination with a series of ruling devices, of a frame, a support movable on the frame and extending longitudinally of the series of ruling devices, actuating means for the ruling devices mounted on the support, and a screw adjustably connecting the frame and support. 60
28. In a ruling machine, a ruling device, controlling means therefor comprising an actuating member and contact portions co-operating therewith and being movable with respect to one another to vary the timing of the machine, and means for moving said portions during the operation of the machine. 70
29. A ruling device, actuating means therefor, and controlling means for the actuating means, said controlling means consisting of a rotatable and a non-rotatable member, the latter having portions movable with respect to one another to vary the time of coöperation of the members. 75
30. A ruling device, actuating means therefor, a rotatable controlling member for the actuating means having a contact portion, a coöperating member provided with separated contact projections, and means for varying the distance between said projections. 80
31. In a ruling machine, a ruling device, electromechanical actuating means therefor, a source of electrical energy, and a controlling device interposed between the actuating means and source and including a rotatable contact member, contact members coöperating therewith, and means for varying the position of the last-named contact members about the rotatable member. 85
32. In a ruling machine, a ruling device, electromechanical actuating means therefor, a source of electrical energy, and a controlling device interposed between the actuating means and source and including a contact-wheel, brushes engaging the wheel, and means for varying the position of the brushes about the wheel. 90
33. In a ruling machine, a ruling device, electromechanical actuating means therefor, a source of electrical energy, and a controlling device interposed between the actuating means and source and including a contact-wheel, brushes engaging the wheel, and means for varying the distance between the brushes. 100
34. In a ruling machine, a ruling device, electromechanical actuating means therefor, a source of electrical energy, and a controlling device interposed between the actuating means and source and including a contact-wheel, brushes engaging the wheel, means for varying the position of the brushes about the wheel, and means for varying the distance between the brushes. 105
35. The combination with ruling pens, of a controlling device comprising a contact-wheel, a support, and brushes mounted on the support and engaging the wheel, one of the brushes being movable on the support circumferentially of the wheel. 110
36. In a ruling machine, pens, and controlling means therefor comprising a shaft, a contact-wheel movable by the shaft, a support mounted on the shaft, and a con- 115
- 65 120
- 65 125
- 65 130

tact member carried by the support and coöperating with the wheel.

37. In a ruling machine, pens, and controlling means therefor comprising a shaft, a contact-wheel movable by the shaft, a support mounted on the shaft, means for varying the angular position of the support about the shaft, and a contact member carried by the support and coöperating with the wheel.

38. In a ruling machine, pens, and controlling means therefor comprising a shaft, a contact-wheel movable by the shaft, a support mounted on the shaft and carrying contact-brushes, a nut pivoted on the support, a bearing fixed relatively to the wheel, and a screw mounted to turn in the bearing and engaging the nut.

39. In a ruling machine, pens, and controlling means therefor comprising a contact-wheel, a support adjacent thereto, two brushes mounted on the support, and means for moving one of the brushes on the support circumferentially of the wheel.

40. In a ruling machine, pens, and controlling means therefor comprising a contact-wheel, a support adjacent thereto, a brush carried by the support, a second support movable on that first-named, and a brush carried by the second support.

41. The combination with ruling devices, of plural receiving means, and an electro-mechanical actuating device for the ruling devices adapted to coöperate with any one of a plurality of receiving means.

42. In a ruling machine, a support, a flexible pen mounted thereon, an electromagnet and its armature, and means con-

necting the armature and pen whereby the pen may be flexed to render it ineffective while the support remains stationary.

43. In a ruling machine, a support, a flexible pen mounted thereon, an electromagnet and its armature, means connecting the armature and pen whereby the pen may be flexed while the support remains stationary, and means independent of the pen-flexing means for moving the support.

44. In a ruling machine, a work-support, a flexible pen normally coöperating with said support, a support in which the pen is mounted, an electromagnet and its armature, and means connecting the armature and pen whereby the pen may be flexed to move it from the work-support.

45. In a ruling machine, a plurality of ruling devices, a plurality of actuating means for said ruling devices, a plurality of controlling means for the actuating means, and means for connecting any actuating means with any controlling means.

46. In a ruling machine, a plurality of ruling devices, a plurality of actuating means for said ruling devices, a plurality of controlling means for the actuating means, and means for connecting a plurality of actuating means to a single controlling means.

Signed at Boston, in the county of Suffolk and State of Massachusetts, this 3rd day of October, 1913.

SYLVANUS H. COBB.
